UNITED STATES PATENT OFFICE.

ARTHUR WHITE, OF SHEBOYGAN FALLS, WISCONSIN.

ROTARY MOTOR.

No. 893,045.

Specification of Letters Patent.

Patented July 14, 1908.

Application filed September 13, 1907. Serial No. 392,640.

To all whom it may concern:

Be it known that I, ARTHUR WHITE, residing in Sheboygan Falls, in the county of Sheboygan and State of Wisconsin, have invented new and useful Improvements in Pressure-Expansion Rotary Motors, of which the following is a description, reference being had to the accompanying drawings, which are a part of this specification.

10 This invention relates to improvements in pressure expansion rotary motors.

One of the objects contemplated is to provide a motor having a rotary member within a casing and adapted to receive steam under 15 full boiler pressure at the periphery of the rotating member and to exhaust the same at the center.

Another object is to provide a motor with an inlet passageway extending entirely 20 around the rotary member, so that in starting the motor, steam being admitted to the passageway will cause the same to expand first, thereby preventing binding between the casing and the rotary member.

25 A further object of this invention is to form the casing into a plurality of parts adjustably connected together to provide means for making a very fine adjustment between the working parts.

30 A still further object of this invention is to provide pockets and passageways so positioned and shaped that after the steam has imparted all of its energy to the rotary member it will be free to exhaust through the exhaust opening at the center.

With the above and other incidental objects in view, the invention consists of the motor and parts, or their equivalents, as hereinafter described.

40 Like numerals of references refer to corresponding parts throughout the different views of the drawings.

In the accompanying drawings, Figure 1 is a front view of the motor, the casing and 45 shaft being in section and the rotary member having a part broken away therefrom; Fig. 2 is a vertical section of the motor taken on line 2-2 of Fig. 1; Fig. 3 is a vertical section of the main portion of the motor casing, the rotary member being removed therefrom and a portion of the inner surface being broken away to show one of the passageways; Fig. 4 is a plan view of the rotary member and a portion of the connected shaft; Fig. 5 is a 50 plan view of a fragment of the rotary member

on a large scale, parts broken away and in section; and Fig. 6 is a cross section of a fragment of the rotary member showing the passages between the peripheral pocket and the side pockets.

60

In the drawings the reference numeral 8 indicates a cylindrical shaped member provided with a base portion 9 integral therewith and forming the main portion of the casing, the base portion serving as a support for the 65 motor. The inner portion of the cylindrical shaped member is partially threaded and has connected thereto by means of said threads, face plates 10, 10, the face plates being correspondingly threaded. The face plates 10, 10 70 have centrally outwardly projecting portions provided with adjustable bearings 11, 11 threaded thereto and held in adjusted position by means of jam nuts 12, 12. Journaled in the adjustable bearings 11, 11 and 75 surrounded by packing glands 13, 13 is a shaft 14 which is partially tapered upon both sides of a rotary member 15 rigidly connected thereto and positioned within the cylindrical shaped member and between the face plates. 80 The adjustable bearings are provided with tapered openings corresponding to the taper of the shaft journaled therein, and are adapted to adjust the position of the rotary member 15 with relation to the face plates. 85

The shaft 14 is provided with a pulley 16 for belted connection and application of the power of said motor. The periphery of the rotary member is tapered and the inner surface of the cylindrical member is also tapered 90 coincident therewith providing means of adjustment between the rotary member and the cylindrical member.

The cylindrical member 8 is provided with an inlet passageway 17 extending entirely 95 around the cylindrical portion of the casing 8 and has connected thereto a steam feed pipe 18 connected to a source of supply such as a boiler (not shown) and serving to supply steam under full boiler pressure to said passageway. A series of inlet ports 19, 19 lead inwardly and tangentially in the direction of rotation of the rotary member, and are so positioned in order to direct the jets of steam or fluid under pressure tangentially into the 100 curved pockets 20, 20 coincident therewith and extending almost entirely across the periphery of the rotary member 15 to rotate the same. Passageways 21, 21 connect the curved pockets 20, 20 to angular side pockets 105 110

22, 22 and are adapted to deflect the fluid in the opposite direction by the angularity of said side pockets. Outer pockets 23, 23 in the face plates 10, 10 register radially with the pockets 22, 22 in the rotary member 15. Curved passageways 24, 24 connect the side pockets 23, 23 with inner pockets 25, 25 located closer to the shaft 14. Inner pockets 26, 26 in the rotary member 15 are adapted to register with pockets 25, 25 and also with exhaust pockets 27, 27, which are connected to the tubular portion 28 of the shaft 14.

The pockets 27, 27 are connected together by means of an annular recess 29 to provide a free exhaust from all of the pockets, and to still further enlarge the exhaust passages, annular recesses 30, 30 coincident with the annular recesses of the face plates, are formed in both sides of the rotary member, and radial recesses lead from the annular recesses to the hollow portion of the shaft.

The inlet passageway 17 is provided with a series of six sets of inlet ports 19, 19 and the face plates are likewise provided with a series of six sets of pockets and six exhaust pockets so that fluid under pressure passes from the inlet ports 17 to the exhaust ports 26 in substantially one-third of a revolution of the rotary member. It is obvious, however, that the motor may have any number of series of inlet and outlet ports without departing from the spirit and scope of the invention. The number of pockets may also be changed radially, without departing from the invention.

The inlet passageway 17 is reduced in size near its closed end as it is only necessary to provide a capacity sufficiently large to supply the one series of inlet ports located at this point.

Lugs 31, 31 bolted to the cylindrical shaped member are provided with set screws 32, 32 and are adapted to firmly hold the face plates in adjusted positions with relation to the cylindrical shaped member.

Discharge passages 33, 33 are located at the lowermost portions of the chamber within the cylindrical shaped member to discharge water of condensation which may accumulate therein, and sight gages 34 provided with pet cocks 35 are connected to the passages to control the discharge of the said water of condensation. Oil cups 36, 36 are connected to the face plates and are adapted to lubricate the inner portions of the shaft and the rotary member.

In adjusting the parts after being assembled, the rotary member is positioned so that its tapered periphery will freely turn but remain steam tight with the inner tapered surface of the cylindrical shaped member. The face plates are then turned by means of their threaded engagement with the cylindrical shaped member until the inner surfaces of the face plates just touch the outer faces of the rotary member. The face

plates are then locked in position by means of jam nuts 12 and the set screws 32. An adjustment of the rotary member with relation to the face plates may be made by means of the threaded bearings 11, 11, and the tapered portions of the shaft.

In operation steam or fluid under pressure is admitted to the inlet passageway extending around the cylindrical portion of the casing and passing through the tangential ports in jets forcibly acts upon the wall of the curved pockets in the periphery of the rotary member and causes the rotation of said rotary member. The steam or fluid under pressure will now begin to act by expansion and in expanding will pass through the passageways connecting the curved pockets to the angular side pockets and ejected from the latter pockets in the opposite direction against the walls of the pockets in the face plates and by expansion and reaction add further impetus to the rotating rotary member. The fluid under lessened pressure will continue to expand and will pass through the curved passageways and will again be deflected in the opposite direction and ejected from the inner ports against the walls of the inner pockets of the rotary member and add still further impetus to the rotary member. The fluid in the inner pockets of the rotary member will be carried by said member until said pockets successively come into register with the exhaust pockets in the face plates when each pocket will eject the contained fluid and in ejecting will receive reactionary effect therefrom but in a less degree than formerly described due to the reduced pressure of the fluid. The fluid is now free to pass from the exhaust pockets into the tubular portion of the shaft and be discharged into the atmosphere from the open end thereof.

From the foregoing description it will be seen that a motor is provided which is constructed to receive the full boiler pressure at the periphery of its rotary member where it has the greatest power and leverage, and it is then allowed to impart its remaining energy by expansion as it is successively passed through deflecting passageways and expansion pockets and is finally discharged at the center of the rotary member, the point of least effective back pressure. Provision is also made for making very fine adjustment in assembling the parts and also to compensate for wear.

Another object in applying equal pressure simultaneously around the periphery of the rotary member is to lessen the friction between the shaft and the bearings.

It is obvious that the exhaust opening may be disposed adjacent to the axis of rotation instead of at the axis, without departing from the spirit and scope of the invention.

What I claim as my invention is:

1. In a pressure expansion rotary motor, a rotary member, a casing surrounding the rotary member, means for directing fluid under pressure to pockets formed in the periphery of the rotary member, expansion pockets formed in the adjacent sides of the casing and the rotary member, and means for discharging the exhaust fluid at or near the axis of the rotary member.
2. In a pressure expansion rotary motor, a rotary member, a casing surrounding the rotary member, a pressure fluid passageway in said casing and surrounding said rotary member, tangential ports formed in said casing and constructed to direct fluid under pressure to pockets formed in the periphery of the rotary member, expansion pockets formed in the adjacent sides of the casing and the rotary member, and means for discharging the exhaust fluid at or near the axis of the rotary member.
3. A pressure expansion rotary motor, comprising a rotary member, a casing surrounding the rotary member, means for admitting fluid under pressure to pockets formed in the periphery of the rotary member, pockets formed in the sides of said rotary member and in communication with the pockets formed in the periphery thereof, pockets formed in the casing and positioned to register with said side pockets, and means for discharging the exhaust fluid at or near the axis of the rotary member.
4. A pressure expansion rotary motor, comprising a rotary member, a casing surrounding the rotary member, means for admitting fluid under pressure to pockets formed in the periphery of the rotary member, pockets formed in the sides of said rotary member and in communication with the pockets formed in the periphery thereof, outer pockets formed in the casing and positioned to register with said side pockets and in communication with inner pockets formed in said casing, inner pockets formed in the rotary member and positioned to register with the inner pockets of the casing, and means for discharging the exhaust fluid at or near the axis of the rotary member.
5. A pressure expansion rotary motor, comprising a rotary member, a casing surrounding the rotary member, means for admitting fluid under pressure to pockets formed in the periphery of the rotary member, pockets formed in the sides of said rotary member and in communication with the pockets formed in the periphery thereof, outer pockets formed in the casing and positioned to register with said side pockets and in communication with inner pockets formed in the casing, inner pockets formed in the rotary member and positioned to register with the inner pockets of the casing, exhaust pockets formed in the casing positioned to
- register with the inner pockets of the rotary member, and exhaust passages formed in the rotary member in communication with said exhaust pockets.
6. A pressure expansion rotary motor, comprising a casing, a rotary member within said casing, a shaft upon which the rotary member is mounted, a pressure fluid passageway formed in said casing and surrounding the rotary member, tangential ports leading from said passageway to the periphery of the rotary member, pockets formed in the periphery of the rotary member and positioned to register with the tangential ports, pockets formed in the sides of the rotary member and in communication with the pockets formed in the periphery thereof, and means for discharging the exhaust fluid at or near the axis of the rotary member.
7. A pressure expansion rotary motor, comprising a casing, a rotary member within said casing, a shaft upon which said rotary member is mounted, a pressure fluid passageway formed in said casing and surrounding the rotary member, tangential ports leading from said passageway to the periphery of the rotary member, curved pockets formed in the periphery of the rotary member and positioned to register with the tangential ports, pockets formed in the sides of the rotary member and in communication with the curved pockets, outer pockets formed in the casing and positioned to register with the side pockets, inner pockets formed in the casing and in communication with the outer pockets, inner pockets formed in the sides of the rotary member and positioned to register with the inner pockets of the casing, exhaust pockets formed in the casing and also positioned to register with the inner pockets of the rotary member, and exhaust passages formed in the rotary member in communication with said exhaust pockets.
8. In a pressure expansion rotary motor, a cylindrical shaped casing, face plates connected to said casing, a rotary member within said casing, a shaft connected to the rotary member and mounted in said face plates, a pressure fluid passageway formed in said casing and surrounding the rotary member, tangential ports leading from said passageway to the periphery of the rotary member, pockets formed in the periphery of the rotary member and positioned to register with the tangential ports, pockets formed in the side of the rotary member and in communication with the peripheral pockets, and means for discharging the exhaust fluid at or near the axis of the rotary member.
9. In a pressure expansion rotary motor, a cylindrical shaped casing, face plates adjustably connected to said casing, a rotary member within said casing, a shaft connected to the rotary member and mounted in said face plates, a pressure fluid passageway formed in

said casing and surrounding the rotary member, tangential ports leading from said passageway to the periphery of the rotary member, curved pockets formed in the periphery 5 of the rotary member and positioned to register with the tangential ports, and means for discharging the exhaust fluid at or near the axis of the rotary member.

10. In a pressure expansion rotary motor, 10 a cylindrical shaped casing, face plates adjustably connected to said casing, a rotary member within said casing, a shaft connected to the rotary member and mounted in said face plates, a pressure fluid passageway formed in said casing and surrounding the rotary member, tangential ports leading from 15 said passageway to the periphery of the rotary member, curved pockets formed in the periphery of the rotary member and positioned to register with the tangential ports, pockets formed in the sides of the rotary member and in communication with the curved pockets, outer pockets formed in the face plates and positioned to register with the side pockets, inner 20 pockets formed in the face plates and in communication with the outer pockets, inner pockets formed in the sides of the rotary member and positioned to register with the inner pockets of the face plates, 25 exhaust pockets formed in the face plates and also positioned to register with the inner pockets of the rotary member, and exhaust passages formed in the rotary member in communication with said exhaust pockets. 30
35. 11. In a pressure expansion rotary motor, a cylindrical shaped casing, face plates adjustably threaded to said casing, a rotary member within said casing, a tubular shaft connected to the rotary member and mounted in said face plates, a pressure fluid passageway formed in said casing and surrounding the rotary member, a series of tangential ports leading from said passageway to the periphery of the rotary member, curved pockets 40 formed in the periphery of the rotary member and positioned to register with the tangential ports, pockets formed in the sides of the rotary member and in communication with the curved pockets, outer pockets formed in the face plates and positioned to register with the side pockets, inner 45 pockets formed in the face plates and in communication with the outer pockets, inner pockets formed in the sides of the rotary member and positioned to register with the inner pockets of the face plates, 50 exhaust pockets formed in the face plates and also positioned to register with the inner pockets of the rotary member, and exhaust passages formed in the rotary member in communication with said exhaust pockets. 55
55. 12. In a pressure expansion rotary motor, a cylindrical shaped casing, face plates adjustably threaded to said casing, bearings ad- 60

justably connected to said face plates, a rotary member within said casing, a tubular shaft connected to the rotary member and mounted in said bearings, a pressure fluid passageway formed in said casing and surrounding the rotary member, a series of tangential ports leading from said passageway to the periphery of the rotary member, curved pockets formed in the periphery of the rotary member and positioned to register with the tangential ports, pockets formed in the sides of the rotary member and in communication with the curved pockets, outer pockets formed in the face plates and positioned to register with the side pockets, inner 70 pockets formed in the face plates and in communication with the outer pockets by means of curved passages formed in the face plates, inner pockets formed in the sides of the rotary member and positioned to register with the inner pockets of the face plates, exhaust pockets formed in the face plates and also positioned to register with the inner pockets of the rotary member, annular recesses formed in both the rotary member and the face plates and connecting all of the exhaust pockets together, and exhaust passages formed in both the rotary member and the face plates and connecting the annular recesses to the tubular portion of the shaft. 80

13. In a pressure expansion rotary motor, a cylindrical shaped casing, face plates adjustably threaded to said casing, means for locking the face plates in adjusted position, a rotary member within said casing, a tubular shaft connected to the rotary member and mounted in said face plates, a pressure fluid passageway formed in said casing and surrounding the rotary member, a series of tangential ports leading from said passageway to the periphery of the rotary member, curved pockets formed in the periphery of the rotary member and positioned to register with the tangential ports, pockets formed in the sides of the rotary member and in communication with the curved pockets, outer pockets formed in the face plates and positioned to register with the side pockets, inner 90 pockets formed in the face plates and in communication with the outer pockets, inner pockets formed in the sides of the rotary member and positioned to register with the inner pockets of the face plates, exhaust pockets formed in the face plates and also positioned to register with the inner pockets of the rotary member, annular recesses formed in both the rotary member and the face plates and connecting all of the exhaust pockets together, and exhaust passages formed in both the rotary member and the face plates and connecting the annular recesses to the tubular portion of the shaft. 95

14. In a pressure expansion rotary motor, a cylindrical shaped casing, face plates adjustably threaded to said casing, threaded bolts for locking the face plates in adjusted position, means for discharging the water of condensation from the casing, a rotary mem- 100

105

110

115

120

ber within said casing, a tubular shaft connected to the rotary member and mounted in said face plates, a pressure fluid passageway formed in said casing and surrounding the rotary member, a series of tangential ports leading from said passageway to the periphery of the rotary member, curved pockets formed in the periphery of the rotary member, and positioned to register with the tangential ports, pockets formed in the sides of the rotary member and in communication with the curved pockets, outer pockets formed in the face plates and positioned to register with the side pockets, inner pockets formed in the face plates and in communication with the outer pockets, inner pockets formed in the sides of the rotary member and positioned to register with the inner pockets of the face plates, exhaust pockets formed in the face plates and also positioned to register with the inner pockets of the rotary member, and exhaust passages formed in both the rotary member and the face plates and connecting the exhaust pockets to the tubular portion of the shaft.

15. In a pressure expansion rotary motor, a cylindrical shaped casing, face plates adjustably threaded to said casing, threaded bolts for locking the face plates in adjusted position, valve-controlled sight tubes for discharging the water of condensation from the casing, a rotary member within said cas-

ing, a tubular shaft connected to the rotary member and mounted in said face plates, packing glands surrounding said shaft, a 35 pressure fluid passageway formed in said casing and surrounding the rotary member, a series of tangential ports leading from said passageway to the periphery of the rotary member, curved pockets formed in the periphery of the rotary member and positioned to register with the tangential ports, pockets formed in the sides of the rotary member and in communication with the curved pockets, outer pockets formed in the face plates and 40 positioned to register with the side pockets, inner pockets formed in the face plates and in communication with the outer pockets, inner pockets formed in the sides of the rotary member and positioned to register with the inner pockets of the face plates, exhaust pockets formed in the face plates and also positioned to register with the inner pockets of the rotary member, and exhaust passages formed in both the rotary member and the 45 face plates, and connecting the exhaust pockets to the tubular portion of the shaft.

20. In testimony whereof, I affix my signature, in presence of two witnesses.

ARTHUR WHITE.
